(57) **CLAIM**

The ornamental design for a bottle, as shown and described.

DESCRIPTION

FIG. 1 is a side view of a bottle according to my invention; FIG. 2 is a perspective view thereof; FIG. 3 is a bottom view thereof; FIG. 4 is a top view thereof; and, FIG. 5 is a front view thereof.

The broken lines shown are included for the purpose of illustrating the unclaimed portions of the bottle and form no part of the claim.

All sides not shown form no part of the claimed design.

1 Claim, 5 Drawing Sheets
